UNITED STATES PATENT OFFICE.

GREGORY JOHN SPOHRER, OF FRANKLIN, PENNSYLVANIA, ASSIGNOR TO WILSON MOTOR STARTER COMPANY, OF FRANKLIN, PENNSYLVANIA.

ENGINE-STARTER.

1,072,267.

Specification of Letters Patent.

Patented Sept. 2, 1913.

Application filed June 29, 1911. Serial No. 635,930.

To all whom it may concern:

Be it known that I, GREGORY J. SPOHRER, a citizen of the United States, and a resident of Franklin, in the county of Venango and State of Pennsylvania, have invented a new and Improved Engine-Start, of which the following is a full, clear, and exact description.

My invention relates to a new and improved form of engine starter more especially adapted for use on road vehicles, particularly to that class of vehicles driven by internal combustion engines where it is necessary to start the sparking mechanism by "turning over" the engine shaft, forming an improvement on the construction outlined in my Patent No. 998,418, July 18, 1911.

An object of my invention is to provide a device by means of which the engine shaft may be "turned over" by an automatic compressed-fluid-actuated device controlled from adjacent the operator's seat, without the necessity of manually cranking as is now common with devices of this character.

I attain the above-outlined object by making use of compressed air to actuate a piston movable in a compressed air cylinder, the stem of which piston is adapted to engage the main shaft of the engine to rotate the same through one revolution, and, further, I provide means whereby the piston is automatically returned to its initial position at the end of the stroke.

With the above and other objects in view, as will more fully hereinafter appear, the present invention consists in certain novel details of construction and arrangement of parts hereinafter fully described, illustrated in the accompanying drawings, and more particularly pointed out in the appended claims.

Reference is to be had to the accompanying drawings, forming a part of this specification, in which similar characters of reference indicate corresponding parts in all the figures, and in which—

Figure 1 is a side elevation of an automobile in outline, showing a preferred embodiment of my invention in position thereon; Fig. 2 is a vertical longitudinal section on the line 2—2 of Fig. 4; and through the axis of the main driving shaft; Fig. 3 is a transverse sectional view taken on the line 3—3 of Fig. 2, showing certain parts

in detached position; and Fig. 4 is a transverse sectional view taken on the line 4—4 of Fig. 2.

In the several figures I have shown a compressed air tank A leading from which is a pipe connection B, by means of which compressed air is conveyed to a valve control C disposed in the floor of an automobile D and convenient to the operator. From the valve control C, fluid is conveyed through pipes E and F to a cylinder G, which cylinder has a casing H extending from the forward part thereof and surrounding the main driving shaft J of the engine. This cylinder and casing and its connecting parts constitute the subject matter of my invention. The valve control C comprises a casting extending vertically through and to one side of the center of which is a vertically-extending bore 5, the upper portion of which is enlarged at 6 to form a valve seat 7, which enlarged portion 6 is closed by means of a screw-threaded cap 8, said cap being recessed at 9. Slidably mounted in the bore 5 is a valve stem 10, the head 11 of which is forced into engagement with the valve seat 7 by means of a compressed spring 12, which spring has its lower end resting on the head 11 and its other end positioned within the recessed portion 9. Extending at right angles to the enlarged portion 6, is an inlet 13 in fluid connection with the pipe connection B from the compressed air tank A. Extending from the bore 5 below the head 8, is a downwardly-inclined outlet 14 in fluid connection with a pipe E extending to the cylinder G. On the opposite side of the center of the valve control C is a valve construction 15 identical with the valve construction hereinbefore described in detail, a pipe connection F extending from an inlet 13' to another portion of the cylinder G, and an outlet 14' open to the atmosphere.

Mounted centrally in the valve control C is a plunger 16, the lower end of which is pivoted at 17 to the long arm 18 of a lever 19 fulcrumed at 20 to a lug 21 depending from the under side of the valve control C. The ends of the lever 19 are positioned in vertical alinement below each of the bores 5, and resting upon the ends of the lever and extending into the lower open end of each bore 5 is a plug 22, so positioned below the valve stem 10 that with the lever in the po-

sition shown in Fig. 3 with the short end 23 in depressed position, the plug 22 will be out of engagement with the stem 10, permitting the spring 12 to force the valve to its seat, so as to close communication between the inlet 13 and the outlet 14. As shown to the left of the valve control in Fig. 3, the plug 22 may be forced by the arm 18 to lift the valve off its seat against the action of the spring, thereby permitting fluid communication through the inlet 13' and outlet 14'. The valve control C has a centrally disposed recess 24, and in said recess and surrounding the plunger 16 is a compression spring 25, the lower end of which bears on the bottom of the recess 24, and the upper end of which bears against a collar 26 surrounding the plunger 16 and held in position adjacent the top of the recess 24 by means of a pin 27. By this construction it is seen that the valve control normally maintains the valves in the position indicated in Fig. 3, that is, with the valves closing the passage of compressed fluid from the tank A and maintaining the cylinder G open.

The pipe E extends forwardly, as shown in Fig. 1, to a boss 28 extending upwardly from the casing H. This boss is recessed vertically, in which recess is disposed a plunger 29, the upper end of which has a valve head 30 adapted to rest upon a valve seat 31 formed by an enlargement 32 at the upper end of the recess. The enlarged portion is closed at the top by means of a cap 33, to which cap is fastened the pipe E. Below the valve seat 31 is an outlet 34, by means of which fluid is conveyed through a pipe 35, which pipe is bifurcated at 36, one arm 37 of which bifurcated part leads to an inlet port 38 in one end of the cylinder G and the other arm 39 of which connects to and forms part of the pipe F. As shown, with the valve in the position indicated in Fig. 3, compressed air may be admitted through the pipe E, outlet 34, and inlet port 38, to act on the piston head 40 to drive the same in the direction indicated by the arrow in Fig. 3. The piston stem 41 has a rack 42 depending from the under side thereof, the teeth of which rack engage the gear wheel 43 mounted on a brass sleeve 44 loosely mounted on the driving shaft J. Disposed on the upper surface of the piston stem 41, is a bearing plate 45 extending from the front end 46 about two-thirds of the distance toward the piston head 40, the end adjacent the piston head being beveled at 47. The lower end 48 of the plunger 29 is adapted to bear on the plate 45 to hold the valve head 30 off its seat 31. It will be seen by this construction, that as the piston stem is advanced in rotating the gear wheel 43, the plate will hold the valve head 30 off its seat until the enlarged end 48, in effect, slides

down the incline 47, thereby permitting the spring 49 to force the valve head 30 on to its seat 31, thereby closing the passage of the compressed fluid through the outlet 34 and shutting off the compressed fluid from the left-hand side of the piston head 40.

Pivoted to one side of and adjacent to the front end 46 of the piston stem 41, is a tumbler 50 in the form of a bell crank lever, one arm 51 of which has an upwardly and rearwardly extended beveled edge 52, up which edge or incline is adapted to slide, during the outward travel of the piston stem 41, the end 53 of a lever 54 fulcrumed at 55 to a broad flat arm 56, through the tubular portion 57 of which extends a shaft 58, the ends of which are mounted in the casing H to form a pivot for the arm 56, which arm is bifurcated to form a wide spreading yoke 59, the arms 60 of which extend in the plane of the arm 56 and in a plane at right angles to the axis of the driving shaft J. Extending inwardly from the end of the arms 60 are alined roller bearings 61 adapted to roll in a peripherally-disposed recess 62 in the clutch member 63, feathered on the shaft J by means of a key 64. The side of the clutch member 63 adjacent the gear wheel 43 has clutch teeth 65 adapted to engage the teeth 66 on the side of the gear wheel 43, thereby connecting said gear wheel 43 with the driving shaft J. It will be noted that as the piston stem is driven forward, the tumbler 50 raises the end 53 of the lever 54, compressing the spring 67 disposed between the end of the lever opposite the end 53 and the tubular portion 57, to throw the clutch member 63 into engagement with the gear wheel 43, so that the motion of the gear wheel will be transmitted through the clutch member 63 and key 64 to the drive shaft J.

As shown more particularly in Fig. 2, the piston stem 41 is wider than the gear wheel 43, a portion 68 of the rack 42 extending beyond the side of the gear wheel 43 opposite the side upon which the clutch member is mounted. This extended portion is permanently in engagement with the teeth of the gear wheel 69 having a hub 70 loosely mounted on the driving shaft J and projecting from the gear wheel in a direction opposite to the gear wheel 43. Since the teeth 68 of the rack at the end 46 are short and engage only with the gear 69, there is formed adjacent thereto a blank space 42' on the stem 41, to permit the disengagement of the stem from the gear 43. Surrounding the extended hub 70 is a flat spiral spring 71, the inner end of which is fastened to the gear wheel 69 at 72, and the outer end of which is fastened to the side of the casing H at 73. It will be seen that by this connection, as the piston stem 41 moves forward, the teeth 42 and 68 rotate the gear 130

- wheel 69, and as this gear wheel revolves, the spring 71 is coiled, placing the same under tension, and by the time the piston rod has reached the limit of its forward movement in rotating the shaft J, the engine will have taken up the rotation of the shaft, which rotation of the shaft will throw the clutch member 63 out of engagement with the gear wheel 43, thereby permitting the gear wheel 43 to ride idle on the shaft J. The coiled spring 71 will assert itself to reverse the direction of movement of the gear wheel 69, thereby feeding the rod 41 back to its initial position shown in Fig. 3. The head 40 is cushioned in its return by a hollow sleeve 74 extending rearwardly from said head, which sleeve 74 is held in its extended position by means of a compressed spring 75 disposed in a recess 76 centrally disposed in the head 40 and stem 41 and bearing on said stem and sleeve. The tumbler 50 is pivoted at 77 and is held in the position shown in Fig. 3 by means of a spring 78, and the tumbler is prevented from rotating under the action of the spring by means of a stop pin 79. By means of this construction of the tumbler and due to the fact that the lever 54 is pivoted, the tumbler will swing on its pivotal point 77 and will permit the end 53 of the lever 54 to pass said tumbler 50, thereby placing the same in position to throw the clutch member into engagement with the gear wheel 43 when the device is again actuated.
- To start the engine, the operator depresses the plunger 16, swinging the lever 19 to force the valve head 11 off its seat 7, thereby permitting compressed air to pass from the tank A through the pipe B, inlet 13, outlet 14 of the valve control C, through the pipe E, outlet 34, pipe 35 and inlet port 38 of the cylinder G, to act on the head 40, forcing the stem 41 in the direction indicated by the arrow. At the same time that the valve head 11 is raised off its seat 7, the valve 15 closes the outlet 14'. As the piston stem moves forward, the tumbler 50 will cause the yoke 59 to swing the clutch member 63 mounted on the main drive shaft J into engagement with the gear wheel 43, which gear wheel is then being rotated by means of the rack depending from a piston rod 41. At the same time, the rack 42 will cause the spring 71 to tighten. As the stem advances, the plunger 48 will move down the incline 47, thereby shutting off the passage of the compressed fluid to the cylinder G and permitting the compressed air in the rear of the head 40 to force the head substantially to the forward end of the cylinder G. This movement will rotate the shaft J, and such movement of the shaft will start the engine as is common with the cranking method now in use. The shaft J rotating by means of its engine will disconnect the teeth 65 of the clutch member 63, throw the clutch member out of engagement with the gear wheel 43, and as the compression in the cylinder G is reduced by the opening of the exhaust port the spring 71 is free to rotate the gear wheel 69 backward, forcing the stem 41 back to its initial position as shown in Fig. 3. Removing the foot pressure from the rod 16 will permit the spring 25 to act, thereby restoring the valves to the position shown in Fig. 3 and permitting the exhaustion of the expanded fluid from the rear of the head 40 through the arm 37 and pipe 35, through the pipe F, inlet 13' and outlet 14' to the outside atmosphere.
- Having thus described my invention, I claim as new and desire to secure by Letters Patent:
1. In an engine starter, a casing, an engine shaft passing through said casing, a clutch member feathered to said shaft, a yoke pivotally supported above said clutch member and engaging the same to slide said clutch member longitudinally along said shaft, said clutch member having teeth on one side thereof, a gear wheel loosely mounted on said shaft having teeth on the side thereof adapted to engage the teeth of the clutch member, a second gear wheel loosely mounted on said shaft on the side of said first-mentioned gear wheel opposite the clutch member, a piston stem having a rack on the under side thereof, means actuating said piston stem, said rack engaging both of said gear wheels, a tumbler carried by said piston stem, said tumbler adapted to engage said yoke during the initial movement of said stem to throw the teeth of the clutch member and gear wheel into engagement, so that the further movement of said stem will rotate said shaft, and spring means attached to said second-mentioned gear, placed under tension by the movement of said stem while rotating the shaft, said spring means acting on said second-mentioned gear to return said stem to its initial position.
2. In an engine starter, a main engine shaft, a casing mounted on said shaft, a clutch member keyed to said shaft, a gear wheel loosely mounted on said shaft and adapted to engage said clutch member, a piston cylinder, a piston stem projecting from said cylinder, said stem having a rack thereon adapted to engage said gear wheel, means for admitting compressed fluid to said cylinder, to drive said piston stem in a direction to rotate said gear wheel and clutch member, a second gear wheel loosely mounted on said shaft adjacent the first-mentioned gear wheel, and a coil spring having one end connected to said last-mentioned gear wheel and the other end attached to said casing, to react on said last-mentioned gear wheel and piston stem to return the latter to its initial position.
3. In an engine starter, an engine shaft,

- a clutch member keyed to said shaft, a gear wheel loosely mounted on said shaft and adapted to engage said clutch member, a piston stem having a rack thereon engaging 5 said gear wheel to rotate the same, a pivoted yoke loosely engaging said clutch member to move the same on said shaft into engagement with said gear wheel, and a tumbler carried by said stem to actuate said yoke to engage 10 said clutch member and gear wheel.
4. In an engine starter, a shaft, a pair of gear wheels loosely mounted on said shaft, compressed fluid controlled means engaging said gear wheels to rotate the same, means 15 whereby one of said gear wheels is connected to said shaft to rotate the same, and means connected to the other of said gear wheels to return said fluid controlled means to its initial position after it has rotated the 20 gear wheels and shaft.
5. In an engine starter, in combination, an engine shaft, a gear wheel mounted upon and adapted to rotate said shaft, a second gear wheel having a hub loosely mounted 25 upon said shaft, a coil spring mounted upon said hub and adapted to actuate said second-mentioned gear wheel, a reciprocating rack permanently engaging said second-men-

tioned gear wheel and engaging said first-mentioned gear wheel for a portion of its 30 stroke, said rack having a blank space thereon to permit said first-mentioned gear wheel to ride idly on the engine shaft.

6. In an engine starter, an engine shaft, a sliding clutch member feathered to said 35 shaft, a pivoted yoke loosely engaging said clutch member, an arm integral with said yoke, a lever fulcrumed intermediate its length to said arm, a compression spring between one arm of said lever and said yoke, 40 and actuating means adapted to rotate said shaft through said clutch member, said means having a tumbler thereon adapted to engage the arm of said lever opposite the spring-pressed arm, whereby said tumbler 45 will actuate said lever and yoke through said spring, to actuate said clutch member to engage the actuating means.

In testimony whereof I have signed my name to this specification in the presence of 50 two subscribing witnesses.

GREGORY JOHN SPOHRER.
